J. STROOP.

Grain Cleaner.

No. 96,630.

Patented Nov. 9, 1869.

Jacob Stroop

United States Patent Office.

JACOB STROOP, OF JOLIET, ILLINOIS.

Letters Patent No. 96,630, dated November 9, 1869.

IMPROVEMENT IN GRAIN-CLEANERS.

The Schedule referred to in these Letters Patent and making part of the same.

Be it known that I, JACOB STROOP, of the city of Joliet, in Will county, and State of Illinois, have invented a new and useful Improvement on a Grain-Cleaner; and I do hereby declare the following to be a full, clear, and exact description of the same, reference being had to the annexed drawings, making a part of this specification, in which—

Figure 1 is a perspective view of the machine;

Figure 2, a vertical section through the centre of said machine;

Figure 3, a plan view on the top of the upper burr;

Figure 4, a plan view on the bottom of the same;

Figure 5, a plan view on the top of the lower burr;

Figure 6, a cross-sectional view of the inner ring of the upper burr;

Figure 7, like view of the outer ring of the upper burr;

Figure 8, a cross-sectional view of the face-plate of the middle trough of the lower burr;

Figure 9, a like view of the face-plate of the outer trough of the lower burr; and

Figure 10, a like view of one of the teeth on said plates.

My invention consists in the construction of a machine for rubbing and cleaning grain, and the construction and operation of which, I will now proceed to explain.

a is a frame, constructed of suitable pieces of timber, framed together in the manner substantially as shown in fig. 1, with keys *h* to raise and lower the cross-pieces *c*, in the manner hereinafter described.

F is a case, resting in the frame *a*, in which case are two burrs, the one in fig. 5, which is stationary, forming the bed, and the one shown in figs. 3 and 4, the upper burr, which is attached to the spindle, with which its face is at right angles.

The spindle *A* rests upon the cross-piece *D* in the step *R*, in which it revolves, while the upper end is held in place by a box in the cross-bar *I*.

The upper burr is constructed with four radial arms, *m*, to which are attached two concentric rings, 5, fig. 2.

The inner ring presents a flat face to the lower burr, and the outer ring, a circular face, as shown in fig. 2.

These rings are faced with metal, cast in sections, and bolted to the face of the burrs, as shown in figs. 4 and 5, which metal facings have triangular or V-shaped teeth or projections, as shown in said figures, also in figs. 6 and 7.

Fig. 6 is a cross-sectional view of the inner ring, with the metal face attached, by means of a bolt passing through, and fig. 7 is a cross-sectional view of the outer ring, with its metal face.

The lower burr is divided into three annular concentric troughs, by means of the partitions 8, shown in figs. 2 and 5, into the two outer ones of which, the annular rings 5 revolve, as shown in fig. 2.

u are flights, attached to the lower side of the upper burr, radiating from the main shaft *A*, as shown in figs. 2 and 4, and travel in the trough 1.

The lower burr *P* is faced with metal plates, shown in figs. 2, 8, and 9, cast in sections, and fastened by means of screws passing through, as shown.

These plates have triangular or V-shaped projections or teeth, the same as those on the plates of the upper burr, with the exception that they point in the opposite direction.

The operation of the machine is substantially as follows:

The grain is let into the spout *K*, down into the circular trough 1, from whence it is carried around by the flights *u*, figs. 2 and 4, and through into the circular trough 2, through the opening *v*, fig. 5, where it is carried around and operated upon by the teeth or projections on the rings of the upper burr, as it revolves, (the burr being so set as not to grind or break the kernel,) and is finally thrown into the outer circular trough, by the centrifugal force of the upper burr, through the opening *w*, fig. 5, and is finally discharged through the discharge-spout *r*, and leaves the machine.

It will be seen, that by having the teeth set in opposite directions, thus <>, the grain is kept in the centre of the trough, in a great degree, causing the grain to rub hard together, producing friction to clean it better than if the grain were distributed over the entire surface of the burr or trough.

It is in this keeping of the grain together, to produce a friction of its own, that my invention consists, which I find can best be accomplished by burrs, constructed with such faces, as is shown.

The partitions 8 are used so as to cause the grain to travel a greater distance, and, consequently, get a more thorough rubbing, and may be multiplied, as the case may require.

The outer trough is made circular in the bottom, to gather the grain more rapidly, so that it will discharge quicker than if it were flat.

The whole machine is driven by means of a band on the pulley *S*.

Having thus described my invention,

What I claim as new, and desire to secure by Letters Patent, is as follows:

1. The lining or facing the burrs, shown in figs. 2, 3, 4, and 5, with metal plates, having triangular teeth or projections, constructed, operating, and arranged substantially as described.

2. The annular partitions 8 on the burr *P*, operating and arranged as and for the purposes set forth.

JACOB STROOP.
